PRESSURE OPERATED SWITCH

James T. Cooper and James T. Logan, Atlanta,
Ga., assignors to General Electric Company, a
corporation of New York

Application April 30, 1945, Serial No. 591,100

4 Claims. (Cl. 200—82)

1

This invention relates to a circuit recloser, such as is employed to control the flow of current in electric power circuits, and particularly to devices for the automatic restoration of electric service to power circuits interrupted by temporary or transient disturbances on the line. A particular object of our invention is to provide a circuit recloser which shall be adapted to restore the flow of current in an electric power circuit following its interruption just long enough to allow the circuit to regain its electrical insulating characteristics after these have been temporarily destroyed as by lightning, or other causes.

A more specific object of our invention is to provide a service restorer which shall be operable independent of the magnitude of the current flowing through a fault in the circuit, but which shall employ abnormal currents lower in magnitude than necessary to operate conventional restorers or breakers to control an external source of energy capable of operating the circuit restorer in a predetermined manner.

A still more specific object of our invention is to provide a circuit recloser which shall employ an explosive, such as gun powder, as its external source of energy, and which shall be adapted to close a circuit repeatedly a predetermined number of times upon abnormal conditions occurring.

A still further object of our invention is to provide a circuit restorer employing an explosive as an external source of power for opening the circuit and which shall employ the explosive force to inject a deionizing agent into the path of the arc formed incident to the breaking of the circuit.

In accordance with our invention we provide a circuit restorer employing an explosive for opening the switch, which explosive shall be detonated responsive to an overload in the circuit controlled. A repeating mechanism is included in the apparatus for positioning another explosive charge each time the switch is opened. The switch may be reclosed by energy stored up in a spring and will reclose immediately the opening force is released. If the fault or overload continues, the switch is repeatedly opened and a controllable pressure is built up in an auxiliary chamber by successive operations of the apparatus, which pressure is utilized to operate a lock-out mechanism which locks the switch open until it is restored manually. A further feature of our invention comprises the injection of a deionizing agent into the arc formed by the opening of the switch, which deionizing agent may be included in the explosive or in a separate vessel through

2

which a part of the explosive charge is shunted.

Apparatus embodying features of our invention is illustrated in the accompanying drawing, forming a part of this application, in which

5 Fig. 1 is a vertical sectional view through a circuit restorer embodying features of our invention; and

Fig. 2 is a horizontal sectional view taken along the lines II—II of Fig. 1.

10 Referring now to the drawing for a better understanding of our invention, we show an electric circuit embodying conductors 10 and 11 electrically connected to connectors 12 and 13 which lead to a switch having stationary contacts 16 and 17 and a movable or bridging contact 18. For simplicity of illustration, only a single phase is shown but it will be apparent to those skilled in the art that the invention is applicable to multi-phase circuits.

20 The switch just described is mounted in a cylinder 19 having a piston 21 therein connected to the bridging contact member 18 and having a piston rod 22 extending upwardly through the cylinder cover 23. The cylinder cover 23 is 25 mounted on the cylinder 19 in a fluid tight manner, and a packing nut 24 insures a fluid tight fit between the piston rod 22 and the cover 23. A spring 26 is located in the cylinder 19 above the piston 21 and serves normally to hold the switch 30 closed, that is with contacts 16 and 17 bridged by the member 18. The cylinder 19 is provided with an adjustable orifice valve 27 located above the piston 21, when the switch is closed, which valve serves to release pressure from the cylinder after the piston 21 has moved upward a sufficient distance to open the switch.

The cylinder 19 is mounted on a base 28, which in turn may be supported from any suitable stationary support, such as a cross arm 29. The 40 base 28 is formed of two parts held together by means of bolts 31 which define between them a magazine chamber 32 in which is located a magazine 33 mounted for rotation within the chamber about a pin 34. Also, the base 28 defines an 45 explosion chamber 36 which communicates with the lower end of the cylinder 19 and with the magazine chamber 32. The magazine 33 is adapted to contain a plurality of cartridges 37, each containing an explosive and which are 50 adapted to be positioned, one at a time, in communication with the explosion chamber 36. The magazine chamber 32, at one side, is provided with a removable cover 38 so that the cartridges 37 may be inserted in and replaced in the magazine.

The cartridges 37 are detonated, one at a time, by means of a firing pin 39 carried by a solenoid 41. The windings 42 of the solenoid are energized from a circuit 43 which in turn is energized from a transformer 44 upon an overload, such as might be caused by lightning or by grounding of the power circuit illustrated by the conductors 10 and 11.

The magazine 33 is rotated step by step by means of a flexible wire 46 encased within a sheath 47 and connected at its upper end to a lever 48, which is pivoted intermediate its end at 49 to the side of the cylinder cover 23 and which is connected at its other end by means of a slotted connection, to the upper end of the piston rod 22. Located within the magazine chamber 32, at one side thereof, is a guide 52 upon which is mounted a crosshead 53 carrying a pawl 54. The lower end of the wire 46 is connected to the crosshead 53 so that each time the piston 21 moves upwards, the wire 46 is forced downwards and inwards of the magazine chamber 32 and the pawl 54 engages a notch 56 in the magazine 33. Then when the spring 26 forces the piston 21 downwards, the wire 46 is pulled upward and outwards of the chamber 32 thereby rotating the magazine one step and placing another cartridge above the detonator 39. A spring latch 55 mounted in the side of the chamber 32 engages a notch 56 each time the magazine is rotated a step and holds it against accidental displacement.

At 57, on the piston rod 22, we provide a latching notch and mount on top of the piston cover 23 a latch 58 adapted to engage in the notch 57 and hold the piston 21 in its raised position with the switch open. The latch 58 is pressed towards the piston rod 22 by means of a spring 59. Connected to the cylinder 19, near the upper end thereof, is a relatively small auxiliary cylinder 61. A passage 62 establishes communication between the cylinder 19 and the auxiliary cylinder 61 and has located therein a check valve 63. Located within the auxiliary cylinder 61 is a piston 64 which is biased upwardly by means of a spring 66. A piston rod 67 extends upwardly through the cover 68 of the cylinder 61 and engages in a notch 69 of the latch 58, thereby holding it back out of the way of the piston rod 22. A packing nut 71 prevents leakage around the piston rod 67. Upon repeated operation of the piston 21 in opening the switch, pressure is built up in the auxiliary cylinder 61 and when such pressure becomes strong enough to overcome the spring 66 beneath the piston 64, the piston is forced downwardly, disengaging the rod 67 from the notch 69 and thereby allowing the spring 59 to force the latch 58 inwardly to engage the notch 57 on the piston rod 22 and lock the switch open. The pressure accumulated in the cylinder 61 may be controlled as by means of an adjustable valve 72 and the point at which the switch will be locked open thereby controlled. Once the switch is locked open, it may be released manually by means of a handle 70 on the latch 58.

It will be seen, with our improved apparatus, that when the switch is opened by the power of the explosive contained in one of the cartridges 37, that the explosive gases are blown directly upwardly through the explosion chamber, or passage 36 into the cylinder 19 and thereby aid in quenching the arc formed by opening the switch. In order to further aid in quenching the arc, we may provide a deionizing agent in the cartridges 37 which will be volatilized by the heat of the explosion and carried with the explosive gases into

the arc. A number of such agents are known and have been employed in other ways, and we make no specific claim of novelty to any particular such agent. We may also provide, alongside the cylinder 19, a chamber 73 having a screen 74 in the bottom thereof, which carries a suitable deionizing agent 75 above the screen. The chamber 73 is connected to the explosive chamber 36 by means of a conduit 77 and a conduit 78 leads from the upper part of the chamber, above the screen 74 to the cylinder 19 directly in front of the contacts 16 and 17, entering the cylinder at 79. With this arrangement, a part of the gases of explosion are shunted through the conduits 77 and 78, and chamber 73, carrying with them a part of the deionizing agent, volatilized by the heat of the explosive gases, and blown directly into the path of the arc formed by opening the switch.

From the foregoing it will be apparent that we have devised an improved service restorer of the character described which utilizes the force of an explosive as an external source of power for opening the switch, together with automatic means for closing the switch, and other means operable upon a predetermined number of successive openings of the switch to lock the switch in open position. It will furthermore be seen that we have utilized the explosive force, as well as the heat of explosion, to inject a deionizing agent into the arc formed by opening the switch.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are specifically set forth in the appended claims.

What we claim is:

1. In apparatus of the character described, a switch, switch opening means comprising a cylinder, a piston in the cylinder operatively connected to the switch, an explosive charge disposed to create sudden pressure within the cylinder to operate the piston and open the switch and to discharge the gases of explosion around the switch, a deionizing agent carried by the explosive charge, a spring for closing the switch, a pressure accumulator cylinder connected to the first mentioned cylinder and adapted to accumulate pressure responsive to successive operations of the piston, and means operable responsive to a predetermined pressure in the accumulator cylinder to lock the switch open.

2. In apparatus of the character described, an electric circuit, an operating cylinder, a switch controlling the circuit and disposed within the cylinder, a piston in the operating cylinder connected to the switch, a magazine, a plurality of explosive charges carried by the magazine, means responsive to an overload in the circuit for detonating an explosive charge, a spring acting against the piston for normally holding the switch in closed position, a latch for engaging the piston with the switch in open position, an accumulator cylinder, a piston in the accumulator cylinder, a detent carried by the piston for normally holding the latch in disengaged position, and means responsive to successive operations of the operating cylinder in opening the switch to create pressure in the accumulator cylinder to release the latch, and means for adjusting the pressure accumulated in the accumulator cylinder.

3. In apparatus of the character described, an electric circuit, an operating cylinder, a switch controlling the circuit and disposed within the cylinder, a piston in the cylinder connected to the switch, an explosion chamber in communication with the cylinder, a magazine mounted for step by step rotation, a plurality of explosive charges carried by the magazine and adapted to be placed successively in communication with the explosion chamber, means responsive to an overload in the circuit for detonating an explosive charge and creating sudden pressure to be discharged into the cylinder around the switch to open it, a spring for closing the switch, mechanism operatively connected to the piston and adapted upon each closing of the switch to place another explosive charge in position to be detonated, adjustable means for accumulating pressure created by successive operations of the piston, and means operable upon the accumulation of a predetermined pressure for locking the switch in open position.

4. A circuit interrupter comprising a chamber, separable contacts disposed in said chamber, means for biasing said contacts toward the closed

5

10

15

20

25

position, piston means in said chamber for opening said contacts, pressure producing means including an explosive charge disposed to operate said piston and to discharge the gases of explosion around said contacts, said charge including as a portion thereof a deionizing agent which is volatilized by the heat of the explosion.
